UNITED STATES PATENT OFFICE.

JOHN EDWARD QUINN, OF PHILADELPHIA, PENNSYLVANIA.

PROCESS OF MANUFACTURING STOCKINGS.

1,303,593.

Specification of Letters Patent. Patented May 13, 1919.

Application filed March 13, 1917. Serial No. 154,495.

To all whom it may concern:

Be it known that I, JOHN E. QUINN, a citizen of the United States, residing in Philadelphia, Pennsylvania, have invented 5 Processes of Manufacturing Stockings, of which the following is a specification.

My invention relates to the manufacture of stockings, and has for its object improvement of the process of manufacturing 10 what is commonly known as "mock-fashioned" stockings.

My invention lies in the use of certain 15 guide stitches, placed in the stocking during the normal knitting operation, whereby the exact amount and location of the material to be cut away in shaping the leg will be clearly marked. This not only eliminates the necessity for "boarding" the stocking preparatory to cutting away the leg portion, 20 but also makes that operation more rapid and insures accuracy, with the consequent avoidance of "seconds" and a saving in both time and expense.

In the accompanying drawings:

25 Fig. 1 is a view in side elevation of so much of a circular stocking machine of the Banner type, as is necessary to an understanding of my invention;

30 Fig. 2 is a sectional plan view of the machine on the line 2—2, Fig. 1;

Fig. 3 is a developed view of the cam ring, showing the positions of the various needles;

35 Fig. 4 is a view in section on the line 4—4, Fig. 3, showing means whereby the cams are raised to needle operating positions;

Figs. 5, 6, 7 and 8 are views showing the various needles;

Fig. 9 is a view in rear elevation showing 40 the stocking with the central guide stitch and the two side marker stitches;

Fig. 10 is a view in side elevation of a portion of the stocking showing the location of the side marker stitch;

45 Fig. 11 is a view showing a modification of the central guide stitch.

Referring to Figs. 9 and 10, *a* denotes the central guide stitch or mock seam which runs down the back of the stocking to a 50 point just above the heel. At each side of

the central stitch *a* is a side marker stitch *b*, located at a distance from the central stitch equal to the depth to which the stocking is to be cut away in shaping the leg. The preferred form of these stitches is a tuck 55 stitch, but it is apparent that any form of stitch or mock seam will answer the purpose.

The stocking blank is knit complete in one continuous operation on a full-automatic machine and the guide and marker stitches placed in the stocking as it is knit. The arrangement of machine parts whereby this may be accomplished is clearly shown in the drawings. 60

1 is the needle cylinder, 2 the cam ring of a stocking knitting machine of the Banner type. At 3 is shown a cam for placing a tuck stitch in the stocking, this tuck stitching device being old and well known in the 70 art. In the present instance the cam 3, co-operating with the various needles, is adapted to form the center guide stitch and the side marker stitches already referred to. In placing the central stitch *a* the long 75 latch, short medium butt needle 4, shown in Fig. 7, is employed. This needle 4 is located, as shown in Fig. 3, at the center of the set of short butt needles in the needle cylinder. During the knitting of the leg the 80 cam 3 is held down in the position it occupies in the drawings while the series of short butt needles is passing by except on alternate revolutions of the cylinder, when it is raised. That is to say, during one revolution of the needle cylinder the cam 3 is held down, but during the succeeding revolution it is held elevated during the time that the short butt (and the long and short 85 medium butt which are interspersed with the short butt) needle series is passing its position.

When the cam 3 is in the elevated position, the needle 4 rides up over the cam and casts the stitches in the usual way but when 90 the cam is down the stitches are not cast owing to the length of the latch. The operation of the cam 3 is well known and is accomplished by means of the arm 6, engaging the cam and connected to the lever 7 100

pivoted at 8 on the shaft 9, which shaft carries a lever 10 bearing a roller 11. The roller 11 is adapted to coöperate with the cam segments 12 and 13 in rocking the shaft 9 and the lever 7 and so raising the cam 3 at the proper intervals. The lever arm 7^a, integral with the arm 7, has attached the rod 14, which connects with the lever 15, pivoted at 16 and having its free end adapted to coöperate with the outer surface of the cam plate 17, carried on the pattern drum shaft 18. The cam plate 17 carries the cam 19, which contacts with and raises the free end of the lever 15 at the point in the knitting process at which it is desired to stop the formation of the central guide stitch *a*. When the cam 19 meets the lever 15, the cam 3 is raised and held in the elevated position, which causes the long latch needle 4 to operate in the manner of the regular short latch needles in the normal stocking knitting operation. The cam 19 will contact with the lever 15 when the knitting has progressed to a point just above the beginning of the heel.

At 20 is shown a cam which operates in conjunction with the cam 3 and the needles 5—5 to place the side marker stitches *b*—*b* in the stocking. The construction of the cam 20 is similar to that of cam 3 with the exception that it has, cut in its face, the channel 21, which is deep enough to allow the long latch, short medium butt needle 4 to pass through but not so deep as to allow the long latch, long medium butt needles 5—5, which are forced to ride over the top of the cam. This channel is necessitated by the fact that in the knitting of the central guide stitch *a*, the needle 4 must be operated to cast its stitches by the cam 3 only, which controls that operation. The needles 5—5, however, are forced over the cam 20 which causes them to knit in the same manner as the short latch needles in the normal knitting of the stocking. When, however, the cam 20 is held down, in the position similar to that of cam 3 in the drawings, the needles 5—5 will be operated in a manner exactly similar to that of needle 4 and by the same cam 3, to form the tuck stitches *b*—*b*. The cam 20 is, therefore, held elevated until the point is reached where it is desired to begin the stitches *b*—*b*, when it is lowered and held so until the stitches, any desired number, have been made, when it is again elevated. This operation is accomplished by means of the arm 22 engaging the cam 20 and connected to the rod 23, which is attached to the lever 24, pivoted at 16. The free end of the lever 24 is adapted to coöperate with the cam 25 on the cam plate 17. This cam 25 is such that it will allow the lever 24 to fall at the proper mo-

ment to start the marker stitches *b*—*b*, and will elevate the lever when it is desired to 65 end them, holding it thus until the proper time for dropping the cam 20 has again arrived.

The operations which follow the removal of the stocking from the machine are well 70 known to those acquainted with the art. In the present case it is only necessary to fold the stocking at the central stitch *a* and cut away the stocking at the rear to the depth of the side marker stitches. The stocking 75 is then welted at the top and pressed, which completes the operation.

In Fig. 11 is shown a modification of the central guide stitch *a*, it being, in this case, started at a point near the middle of the 80 calf so that the mock seam is the exact length of the portion of the stocking to be cut away, in shaping the leg.

The completed stocking is of a very desirable form, having a shaped leg and a 85 seamless foot. The invention, however, resides in the use of the guides at the back and sides, whereby the completed stocking is obtained with the minimum number of operations and with comparative speed and 90 accuracy.

Having described my process and the machinery whereby it may be carried out,

I claim:

1. The process of forming a stocking 95 which consists in knitting the stocking with marker stitches on opposite sides of the center of the back; folding the stocking along the center of the back from the top to the heel; cutting away a portion of the stocking 100 at the back thereof to a depth indicated by the marker stitches to shape the leg; and stitching the cutting edges to form a mock fashioned stocking.

2. The process of forming a stocking consisting in knitting the stocking with a guide stitch extending down the center of the back to a point near the heel; a marker stitch at the side of the central stitch, for indicating the depth of cut; folding the stocking 110 at the central stitch; cutting away a portion of the stocking at the back to a depth indicated by the side marker stitch, to shape the leg; and stitching the cut edges to form a mock fashioned stocking.

3. The process of forming a stocking consisting in knitting the stocking with a guide stitch extending down the center of the back from a point near the middle of the calf to a point short of the heel and a marker 120 stitch at each side of the central stitch for indicating the depth of cut; folding the stocking at the central stitch; cutting away that portion of the leg at the back over which the central stitch extends to a depth 125 indicated by the side marker stitches; and

stitching the cut edges to form a mock-fashioned stocking.

4. The process of forming a stocking which consists in knitting the stocking with a guide stitch extending down to a point near the heel and with a marker stitch at the side of said first stitch for indicating the

depth of cut; folding the stocking at the guide stitch; cutting away a portion of the stocking to a depth indicated by the side 10 marker stitch to shape the leg; and stitching the cut edges to form a mock fashioned stocking.

JOHN EDWARD QUINN.
